(57) **CLAIM**

The ornamental design for a walking frame for disabled, as shown and described.

DESCRIPTION

FIG. 1 is a front perspective view of the walking frame for disabled, showing my new design;

FIG. 2 is a top plan view of the invention illustrated in FIG. 1; FIG. 3 is a left side elevation view of the invention illustrated in FIG. 1, a right side elevation view being the same;

FIG. 4 is a front side elevation view of the invention illustrated in FIG. 1;

FIG. 5 is a rear side view of the invention illustrated in FIG. 1; FIG. 6 is a side view of the invention illustrated in FIG. 1 with one handle adjusted higher; and,

FIG. 7 is a side view of the invention illustrated in FIG. 1, in a folded position.
